UNITED STATES PATENT OFFICE.

ROBERT E. HILL, OF NORTH EAST, PENNSYLVANIA.

DESIGN FOR A GAME-BOARD.

SPECIFICATION forming part of Design No. 26,167, dated October 6, 1896.

Application filed June 6, 1896. Serial No. 594,624. Term of patent 7 years.

To all whom it may concern:

Be it known that I, ROBERT E. HILL, a citizen of the United States, residing at North East, in the county of Erie and State of Pennsylvania, have invented and produced a new and original Design for Game-Boards; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

Figure 1 is a plan view of my design for a game-board. Fig. 2 is a cross-section taken on the line *x x* in Fig. 1.

The leading features of my design consist in a series of concentric circles upon a plain surface cut by radial lines, so that the spaces between the radial lines are divided thereby into segmental divisions.

In the accompanying drawings, illustrating my design, A is a square board, upon which are drawn seven concentric circles B, C, D, E, F, G, and H, forming a central circular space *b* with concentric spaces *c*, *d*, *e*, *f*, *g*, and *h* surrounding it. These spaces are divided into two halves by a heavy line I, ex-

tending vertically through all the said spaces, 30 and from the circle B to the circle G at right angles to the line I are two heavy radial lines J and K, and from the circle C to the circle G are heavy radial lines L, M, N, and O, again subdividing the spaces between the 35 lines I and J and I and K. Between these main radial divisional lines are other fine radial divisional lines further subdividing the annular spaces *c*, *d*, *e*, *f*, *g*, and *h*. The heavy lines K and J stop at the circles B and G and 40 are arranged in line with each other. The heavy lines O, L, M, and N stop at the circles C and G and are arranged at angles of forty-five degrees, the line O being in line with the line M and the line N being in line with the 45 line L. Most of the fine radial division lines between the circles G and H are out of line with the fine radial lines inside the circle G.

Having thus described my design, what I claim is—

The design in a game-board substantially as herein shown and described.

In testimony whereof I affix my signature in presence of two witnesses.

ROBERT E. HILL.
